ANCHOR BOOM FOR A BOAT

Charles J. Schultz, Jacksonville, Fla.

Application November 21, 1956, Serial No. 43,866

Term of patent 14 years

(Cl. D71—1)

Fig. 1.

Fig. 2

Fig. 3.

Fig. 4.

Fig. 1 is a perspective view of an anchor boom for a boat, showing my new design;

Fig. 2 is a front elevation thereof;

Fig. 3 is a rear elevation thereof; and

Fig. 4 is a cross sectional view taken in the direction of the arrows on the line 4—4 of Fig. 3.

I claim:

The ornamental design for an anchor boom for a boat, as shown.
